(57) **CLAIM**

The ornamental design for a bag clip, as shown and described.

DESCRIPTION

FIG. 1 is a front elevational perspective view of a bag clip according to the present invention.

FIG. 2 is a front view of a bag clip of FIG. 1 according to the present invention.

FIG. 3 is a back view of a bag clip of FIG. 1 according to the present invention.

FIG. 4 is a side view of a bag clip of FIG. 1 according to the present invention, the other side view being a mirror image.

FIG. 5 is a top view of a bag clip of FIG. 1 according to the present invention; and,

FIG. 6 is a bottom view of a bag clip of FIG. 1 according to the present invention.

The broken line portions of the disclosure are for illustrative purposes only and form no part of the claimed design.
